UNITED STATES PATENT OFFICE.

CLAUDE H. BIRDSALL, OF NEW ROCHELLE, NEW YORK.

COIN ASSORTER.

Application filed February 1, 1923. Serial No. 616,290.

To all whom it may concern:

Be it known that I, CLAUDE H. BIRDSALL, a citizen of the United States, residing at New Rochelle, in the county of Westchester and State of New York, have invented certain new and useful Improvements in Coin Assorters; and I do hereby declare the following to be a full, clear, and exact description of the invention, such as will enable others skilled in the art to which it appertains to make and use the same, reference being had to the accompanying drawings and to characters of reference marked thereon, which form a part of this specification.

15 This invention relates, generally, to improvements in machines for assorting coins or other articles of varying diameter.

The invention has for its principal object to provide a simply constructed and easily operated device for separating and segregating from a mass of mixed coins, containing several denominations, the coins of each separate denomination; and to such end the device consists essentially of an inclined plane 25 having a series of openings or ports of various sizes, respectively corresponding in width to the several diameters of coins or other objects to be assorted, a novel endless coin propelling means arranged to travel 30 upwardly over said inclined plane and the openings or ports of the latter, and a series of chutes communicating with said openings or ports to lead the separated coins to the various receivers therefor.

35 Other objects of this invention, not at this time more particularly enumerated, will be clearly understood from the following detailed description of the same.

With the various objects of the invention 40 in view, the same consists, primarily, in the novel assorting mechanism hereinafter set forth; and, the invention consists, furthermore, in the novel arrangements and combinations of the several devices and parts, as 45 well as in the details of the construction of the same, all of which will be more fully described in the following specification, and then finally embodied in the claims appended thereto.

50 The invention is clearly illustrated in the accompanying drawings, in which:—

Figure 1 is a side elevation showing a machine embodying the principles of this invention; Figure 2 is a plan view of the same, 55 with portions of the coin propelling mechanism and separator plate broken away to

show underlying structure; Figure 3 is a longitudinal section, taken on line 3—3 in Figure 2, the coin propelling mechanism being shown in elevation; Figure 4 is a fragmentary longitudinal section through the inclined apertured separator plate and the coin propelling mechanism, said view being drawn on an enlarged scale; and Figure 5 is a detail plane view of a coin propelling element, also drawn on an enlarged scale.

Similar characters of reference are employed in all of the hereinabove described views, to indicate corresponding parts.

Referring now to said drawings, the reference character 6 indicates a suitable frame-work upon which the mechanism is supported. Suitably secured in connection with said frame-work is a longitudinal separator plate 7 disposed to extend upwardly from its inner end toward its outer end in an inclined plane.

The reference character 8 indicates a transverse drive shaft, suitably journaled in said frame-work 6 to extend beneath the lower inner end of said separator plate 7, and the reference character 9 indicates a transverse idler shaft which is suitably journaled in said frame-work 6 to extend beneath the upper outer end of said separator plate 7. Fixed on said drive shaft 8 are a pair of drive sprockets 10, one on each side of said separator plate. Fixed on said idler shaft 9 are a pair of sprockets 11, one on each side of said separator plate. Running over the longitudinally opposed sprockets 10 and 11, on each side of said separator plate 7, are endless conveyer chains 12. Secured to and extending between said conveyer chains 12 are a series of transverse conveyer plates 13, which when the mechanism is operatively actuated are caused to successively travel or slide upwardly over the upper surface of said separator plate 7. Each conveyer plate 13 is provided at its respective ends with downwardly turned end flanges 14 which engage over the longitudinal margins of the separator plate 7 intermediate the same and the adjacent conveyer chains, and connected 90

100 with each end flange 14 is a perforate coupling lug 15, through which passes a pivot bolt 16 for operatively attaching the conveyer plates to the said conveyer chains, as illustrated more particularly in Figures 4 and 5 of the drawings. The means for driving the conveyer mechanism, to cause the

conveyer plates 13 to travel or slide upwardly and successively over the separator plate 7, comprises a crank-handle 17 fixed upon one end of said drive shaft 8, or any other desired means for imparting operative motion to said drive shaft and its drive sprockets 10. In order to prevent reverse or downward sliding movement of said conveyer plates relative to said separator plate 7, the drive shaft 8 may be provided with a ratchet wheel 18 with which cooperates a pivoted dog 19, whereby the rotary movement permitted to the drive shaft will be restricted to the desired operative direction.

13 Supported by the frame-work 6, adjacent to but elevated above the lower or receiving end of the separator plate and conveyor mechanism cooperating therewith, is a hopper or pan 20 having an opening in its side wall toward the separator and conveyor mechanism. Extending downwardly from the hopper opening to the receiving end of the separator and conveyor mechanism is a chute 21.

15 The separator plate 7 is provided with several groups of elongated apertures or openings, which vary in width in correspondence to the diameters of various denominations of coins or other articles. For example as shown in the drawings, the reference character 22 indicates a group of apertures or openings of a width corresponding to the diameter of a ten-cent piece, there being as shown, in this instance, three such apertures 35 or openings in a transversely alined row adjacent to the lower end of the separator plate. Next above is a second group of apertures or openings 23 of a width corresponding to the diameter of a penny. Next above 40 is a third group of apertures or openings 24 of a width corresponding to the diameter of a five-cent piece. Next above is a fourth group of apertures or openings 25 of a width corresponding to the diameter of a twenty-five cent piece. Next above is a fifth group 45 of apertures or openings 26 of a width corresponding to the diameter of a half dollar coin. It will be understood that additional groups of such apertures may be provided, 50 as e. g. for accommodating dollar coins if it is so desired. The individual members of each group of apertures or openings are longitudinally alined with corresponding members of the other groups, so that the separator plate is provided with a plurality of longitudinal lines of apertures or openings progressively enlarged in width from the lower end toward the upper end of the same.

60 Each conveyor plate 13 is provided with 65 openings forming pockets 27 corresponding in number to the number of longitudinal lines of apertures or openings provided in the separator plate 7, and so disposed as to travel longitudinally over the successive apertures or openings in each such line

thereof. Said pockets 26 are of a diameter slightly greater than the largest coin or article to be operated upon by the machine, and consequently will not only accommodate the largest coin or article but also will receive or accommodate the smaller sizes as well. In order to assure the centering of the smaller sized coins or articles in the pockets 27 so that the same will be so disposed when deposited in the pockets that they will be alined with the longitudinal axis of the line of apertures or openings of the separator plate over which a given pocket moves, each pocket is provided at its lower side with a centering notch 28 indented in the margin of the pocket, as will be better understood if reference is made to Figure 5 of the drawings.

170 In order to assure a proper distribution of the coins or articles delivered through the chute 21 from the pan or hopper 20 to the several pockets of each conveyer plate 13, the lower end of said chute 21 is provided with a series of concave guide grooves 29 the bottoms of which register respectively 75 in line with the respective pockets of the conveyer plates 13 as the latter move upwardly beneath the chute.

175 Supported by the frame-work 6 so as to be registered beneath each transverse group of apertures or openings provided in the separator plate 7 are receiving chambers into which the coins or articles passing through said apertures or openings fall. As shown, there is a receiving chamber 30 for ten-cent pieces disposed beneath the group of apertures or openings 22; a receiving chamber 31 for pennies disposed beneath the group of apertures or openings 23; a receiving chamber 32 for nickles disposed beneath the group of apertures or openings 24; a receiving chamber 33 for quarters disposed beneath the group of apertures or openings 25; and a receiving chamber 34 for half-dollars disposed beneath the group of apertures or openings 26. The bottoms 100 of the several chambers 30, 31, 32, 33 and 34 are inclined toward one side of the machine, and their low ends are respectively connected by runways or chutes 35 to communicate 105 with the respective collecting boxes or receptacles 36, 37, 38, 39 and 40 adapted to receive the respective assortments of coin or articles which have been separated by the machine.

110 In operation a supply of mixed coins are placed in the hopper or pan 20, whereupon the operator rotates the drive shaft 8 to cause the conveyer mechanism to travel upwardly over the separator plate 7. While the conveyor mechanism is thus actuated, the operator brushes the coins, a few at a time, out of the hopper or pan 20 into the chute 21, so that the same fall through the latter upon the conveyer plates 13, being 115 120

guided by the guide grooves 29 to the pockets 27 of said conveyer plates in each of which a coin will lodge flatwise, and will be centered therein by the centering notch 28. The upward movement of the conveyer plates slide the coins, thus lodged in the pockets 27 upwardly over the surface of the separator plate 7. As the coins are thus slid upwardly over the separator plate 7 they are caused to ride over the apertures or openings 22, 23, 24, 25 and 26, so that the larger coins, which are of too great diameter to pass through the narrower apertures or openings will be carried beyond the latter until an aperture or opening is reached through which they may pass. For example, when coins are assorted or separated, the ten-cent pieces will fall through the apertures or openings 22, while the pennies, nickles, quarters and halves will ride over such apertures or openings; the pennies will fall through the apertures or openings 23 while the nickles, quarters and halves are carried beyond the same; the nickles will fall through the apertures or openings 24 while the quarters and halves continue upward; the quarters will fall through the apertures or openings 25 while the halves continue on; and finally the halves will fall through the apertures or openings 26. It will thus be apparent that the several denominations of coins will be separated one from another, the dimes falling into the receiving chamber 30 to finally pass through a chute 35 into the receptacle 36; the pennies will fall into the receiving chamber 31 thence into the receptacle 37; the nickles will fall into the receiving chamber 32 and thence into the receptacle 38; the quarters will fall into the receiving chamber 33 and thence into the receptacle 39; and the halves will fall into the receiving chamber 34 and thence into the receptacle 40, thus completing the assorting operations and segregating each denomination of coin in a separate receptacle.

It will also be understood that the machine, in a manner similar to that above described, may be readily adapted to sort and segregate articles other than coin, such as buttons, and other disc-like bodies.

I am aware that some changes may be made in the several arrangements and combinations of the various devices and parts, as well as in the details of the construction of the same, without departing from the scope of this invention as set forth in the foregoing specification, and as defined in the appended claims. Hence, I do not limit my invention to the exact arrangements and combinations of the various devices and parts as described in said specification, nor do I confine myself to the exact details of the construction of said parts as illustrated in the accompanying drawings.

I claim:

1. In a device of the kind described, an inclined separator plate having a plurality of apertures of various widths, endless conveyer chains mounted to run parallel to the respective longitudinal margins of said separator plate, transverse conveyer plates interconnected between said conveyer chains so as to be moved upwardly over the surface of said separator plate, said conveyer plates having pockets to receive articles to be sorted, said pockets being disposed to register with and move successively over said longitudinally alined apertures of said separator plate, and said pockets at their lower sides having notches for longitudinally centering the articles deposited therein. 75

2. In a device of the kind described, an inclined separator plate having a plurality of apertures of various widths, endless conveyer chains mounted to run parallel to the respective longitudinal margins of said separator plate, transverse conveyer plates interconnected between said conveyer chains so as to be moved upwardly over the surface of said separator plate, said conveyer plates having pockets to receive articles to be sorted, said pockets being disposed to register with and move successively over said longitudinally alined apertures of said separator plate, and said pockets at their lower sides having notches for longitudinally centering the articles deposited therein, a hopper mounted adjacent to the lower end of said separator plate and conveyer means, a chute leading from said hopper for depositing said articles to be sorted upon the conveyer means, and means beneath the apertures of said separator plate for receiving and segregating the articles dropped therethrough. 90

3. In a device of the kind described, an inclined separator plate having a plurality of apertures disposed in longitudinal succession and alinement extending from the lower end thereof toward the upper end thereof, said apertures being respectively of increased width as they approach said upper end of said separator plate, endless conveyer chains mounted to run parallel to the respective longitudinal margins of said separator plate, transverse conveyer plates interconnected between said conveyer chains so as to be moved upwardly over the surface of said separator plate, said conveyer plates having pockets to receive articles to be sorted, said pockets being disposed to register with and move successively over said longitudinally alined apertures of said separator plate, and said pockets at their lower sides having notches for longitudinally centering the articles deposited therein. 115

4. In a device of the kind described, an inclined separator plate having a plurality of apertures disposed in longitudinal suc-

4
cession and alinement extending from the lower end thereof toward the upper end thereof, said apertures being respectively of increased width as they approach said upper 5 end of said separator plate, endless conveyer chains mounted to run parallel to the respective longitudinal margins of said separator plate, transverse conveyer plates interconnected between said conveyer chains so 10 as to be moved upwardly over the surface of said separator plate, said conveyer plates having pockets to receive articles to be sorted, said pockets being disposed to register with and move successively 15 over said longitudinally alined apertures of said separator plate, and said pockets at their lower sides having notches for longi-

tudinally centering the articles deposited therein, a hopper mounted adjacent to the lower end of said separator plate and conveyer means, a chute leading from said hopper for depositing said articles to be sorted upon the conveyer means, and means beneath the apertures of said separator plate 20 for receiving and segregating the articles 25 dropped therethrough.

In testimony that I claim the invention set forth above I have hereunto set my hand this 10th day of December, 1923.

CLAUDE H. BIRDSALL.
